UNITED STATES PATENT OFFICE.

HARRY HOMEWOOD AND FRANK G. NORMART, OF FRESNO, CALIFORNIA.

REGISTERING DEVICE FOR REPEATING FIREARMS.

1,128,784.

Specification of Letters Patent. Patented Feb. 16, 1915.

Application filed June 19, 1914. Serial No. 846,139.

To all whom it may concern:

Be it known that we, HARRY HOMEWOOD and FRANK G. NORMART, citizens of the United States, residing at Fresno, in the 5 county of Fresno and State of California, have invented a new and useful Registering Device for Repeating Firearms, of which the following is a specification.

One object of the present invention, is 10 the provision of a means which is visible at all times, and which will indicate the number of shells used by the firearm.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed can be made within the scope of what is claimed without departing from the spirit of the invention.

In the drawings Figure 1 is a side elevation 25 partly in section of a repeating firearm equipped with a registering device. Figs. 2 and 3 are diagrammatic views of the register.

Referring to the drawings, the numeral 1 designates the receiver of the firearm, 30 which has disposed therein, the slideable bar or rod 2 which is actuated by the hand grip 2' to operate the breech block 3. Mounted within the receiver is the pivoted member 4 having the projecting arm 5 which is also 35 operated simultaneously with the breech block 3. A rod 6 is connected to the projection 5 and extends through the channel 7 formed in the stock 8, the opposite end thereof being connected to the crank 9 of

the shaft 10 of the counter 11. The dial 40 or indicator 12 is mounted, so that the numerals of the counter are visible at all times. By this mechanism, it will be seen that the number of shells extracted are counted, and thus by deducting such number from the 45 number originally placed in the magazine, the operator readily ascertains the number of shells remaining in the magazine.

What is claimed is:

The combination with a firearm having 50 a stock, said stock being provided with a longitudinal channel therethrough, the channel terminating in a socket open to one side of the stock, a receiver carried by the stock and in communication with the forward end of the channel, and a breech block mechanism mounted in the receiver, of a registering mechanism, including a counter fitting in the socket of the stock, said counter being provided with an operating shaft, 55 an arm carried by the shaft and operable within the socket of the stock, and a rod slidably mounted in the channel and having its ends projected respectively into the 60 socket of the stock and into the receiver, 55 the end projecting into the socket being operably connected to the arm of the counter, the end projecting into the receiver being operably connected to the breech block mechanism.

In testimony that we claim the foregoing 70 as our own, we have hereto affixed our signatures in the presence of two witnesses.

HARRY HOMEWOOD.
FRANK G. NORMART.
